US00D500281S

(12) United States Design Patent **(10) Patent No.:** **US D500,281 S**
Aruga et al. **(45) Date of Patent:** **** Dec. 28, 2004**

(54) AIRCRAFT

(75) Inventors: **Hiroyasu Aruga**, Nagoya (JP); **Hisao Arai**, Nagoya (JP); **Kei Kitadate**, Nagoya (JP); **Takafumi Nakatani**, Nagoya (JP); **Kengo Hayashi**, Nagoya (JP); **Yukihiko Nakata**, Nagoya (JP); **Yasushi Ando**, Nagoya (JP); **Naoki Futatsudera**, Nagoya (JP); **Shinichiro Taura**, Nagoya (JP); **Yuugo Fukuhara**, Nagoya (JP); **Kenji Inaba**, Nagoya (JP); **Kazuhide Shinoda**, Nagoya (JP); **Yuichi Shimbo**, Nagoya (JP)

(73) Assignee: **Mitsubishi Heavy Industries, Ltd.**, Tokyo (JP)

(**) Term: **14 Years**

(21) Appl. No.: **29/204,220**

(22) Filed: **Apr. 27, 2004**

(30) Foreign Application Priority Data

Oct. 27, 2003 (JP) 2003-031660

(51) LOC (7) Cl. **12-99**

(52) U.S. Cl. **D12/319**

(58) Field of Search D12/319-345; 244/12.5, 13, 15, 55, 65

(57) CLAIM

The ornamental design for aircraft, as shown and described.

DESCRIPTION

FIG. 1 is a front view of an aircraft according to the present design;

FIG. 2 is a rear view of the aircraft;

FIG. 3 is a right side view of the aircraft;

FIG. 4 is a left side view of the aircraft;

FIG. 5 is a plan view of the aircraft;

FIG. 6 is a bottom view of the aircraft;

FIG. 7 is a front perspective view of the aircraft;

FIG. 8 is a rear perspective view of the aircraft;

FIG. 9 is a referential front view showing transparent portions of the aircraft;

FIG. 10 is a referential rear view showing transparent portions of the aircraft;

FIG. 11 is a referential plan view showing transparent portions of the aircraft;

FIG. 12 is a referential left side view showing transparent portions of the aircraft;

FIG. 13 is a referential front perspective view showing transparent portions of the aircraft; and,

FIG. 14 is a referential rear perspective view showing transparent portions of the aircraft.
